UNITED STATES PATENT OFFICE.

MARION C. WALLS, OF FRANKLIN TOWNSHIP, HENDRICKS COUNTY, INDIANA,
ASSIGNOR OF ONE-HALF TO GEORGE W. WEST, OF AMO, INDIANA.

PNEUMATIC PUMP.

1,305,040.

Specification of Letters Patent. Patented May 27, 1919.

Application filed May 17, 1917. Serial No. 169,196.

To all whom it may concern:

Be it known that I, MARION C. WALLS, a citizen of the United States, residing in Franklin township, in the county of Hendricks and State of Indiana, have invented a new and useful Pneumatic Pump, of which the following is a specification, reference being had to the accompanying drawings, and to the letters and figures of reference 10 marked thereon.

This invention relates to means for pumping or forcing liquid by the use of compressed air, the invention having reference more particularly to a pneumatic pump provided with electrical controlling means so as to be adapted for pumping and delivering water intermittently as may be required. An object of the invention is to provide an improved pneumatic pump that shall be so 15 constructed as to be simple, not liable to become deranged and which shall have few parts liable to suffer from wear in use. Another object is to provide an efficient pneumatic pump of such construction as to be 20 adapted for use in drilled wells and at any required depth and capable of elevating water in a practically continuous flow. A further object is to provide an improved pneumatic pump and controlling means of such 25 construction as to permit intermittent operation and delivery of water only as may be periodically needed, to avoid the cost of providing and maintaining a tank or reservoir for the water. A still further object is 30 to provide a pneumatic pump that shall be of such construction as to be capable of being readily installed in position and permit ready access to the various parts thereof when repairs may be necessary, and which 35 will be durable and economical in use.

With the above-mentioned and other objects in view, the invention consists in a dual pneumatic pump provided with means for automatically controlling the flow of compressed air for the operation of the pump in synchronism with the control of the flow of water from the pump, the pump including novel means for controlling the flow of the actuating air while in operation. The 45 invention consists also further in the novel parts and combinations and arrangements of parts as hereinafter particularly described and further defined in the appended claims.

50 Referring to the drawings,—Figure 1 is

a sectional elevation of a pneumatic pump constructed substantially in accordance with the invention; Fig. 2 is a sectional elevation of the pump partially broken away and omitting a number of features seen in the preceding figure; Fig. 3 is a horizontal section of the pump cylinder on the line III—III on Fig. 1; Fig. 4 is a section on the line IV—IV on Fig. 1; Fig. 5 is a bottom plan view of the pump cylinder; Fig. 6 is a vertical section of the more essential portions of the pump, relatively large parts being broken away; Fig. 7 is a top plan of an improved faucet or valve comprising a feature of the invention; Fig. 8 is a side elevation partially broken away of the improved faucet or valve; Fig. 9 is a perspective view of one of the parts or portions of the lower pump cylinder head; Fig. 10 is a perspective view of one of the foot valves 55 of the pump cylinder; Fig. 11 is a vertical section of one of the check valves for supporting the column of water in the discharge pipe; Fig. 12 is a horizontal section on the line XII—XII on Fig. 6; Fig. 13 is a fragmentary section on the line XIII—XIII on Fig. 6; Fig. 14 is a sectional plan view on the line XIV—XIV on Fig. 6 looking upward; Fig. 15 is a section on the line XV—XV on Fig. 6; Fig. 16 is a sectional elevation of the air-controlling apparatus adapted to be electrically operated and controlled to facilitate the operation and control of the pump; Fig. 17 is a vertical section of one of the governing devices of the 60 pump, taken on the line XVII—XVII on Fig. 15; Fig. 18 is a sectional detail showing one of the appliances relating to the operating mechanism of the pump; and, Fig. 19 is a diagrammatical illustration of the apparatus for electrically controlling the supply of actuating air by means of the faucet or valve provided for controlling the flow of the water.

Throughout the drawings similar reference characters indicate corresponding or like elements or features of construction herein referred to in detail.

The invention contemplates the placing of a pump cylinder in a well tube or casing 1 105 or in any body of liquid in such relation that the pump cylinder shall be immersed in the liquid which is to be elevated by the pump. The pump has practically two operative cylinders but for the purpose of compact con- 110

struction that may be readily admitted into a well casing, a hollow cylinder 2 is provided which has a central partition 3 therein which divides the cylinder into two operative chambers that are provided respectively with bottom heads 4 and 4' and top heads 5 and 5', the cylinder heads preferably being made separately as indicated. The bottom or lower heads are provided respectively with outside hollow guides 6 and 6' and also apertures 7 and 7' respectively on either side of the guides. Foot valves 8 and 8' are movably arranged upon the tops or inner sides of the heads 4 and 4' respectively and have guide stems 9 and 9' thereon that are movably arranged in the guides 6 and 6' respectively, the valves being arranged so as to be lifted to a limited extent by the pressure of the water in which the cylinder is immersed. Preferably the cylinder heads are secured in place by means of rods 10 and 10' that extend through the respective water-chambers. An outlet pipe 11 is arranged in one of the chambers and a similar pipe 12 in the adjacent one of the chambers of the cylinder and extend through and are secured to the upper or top heads 5 and 5' respectively, and a single discharge pipe 13 is connected to the two outlet pipes and is of suitable length to conduct the water or other liquid to the desired height. The lower ends of the pipes 11 and 12 have valve casings 14 and 14' thereon in each of which is a suitable check valve 15, the valve casings being arranged conveniently near to the foot valves. The top of the discharge pipe 13 is provided with a suitable stop cock or valve and preferably comprises a body 16 and a rotary or plug valve 17 provided with a handle 18. Two air-conducting pipes 19 and 20 are connected to the top or upper cylinder heads 5 and 5' respectively and terminate in the upper portions of the respective chambers of the cylinder, the pipes extending upward to a suitable height where it may be desired to arrange the apparatus for controlling the flow of compressed air and the exhaust air through the pipes. The mechanism for automatically controlling the flow of air in the operation of the pump, comprises a plurality of valves and chambers for the valves and, in a convenient form for illustrating the invention, comprise an approximately U-shaped unitary casting having a stem 21 and a relatively thinner stem 22 extending upward from a transverse base portion 23, the stems constituting the body portions or walls of the chambers, the stem 21 having an air-chamber 24 therein to which a supply pipe 25 is connected. The stem 21 of the casting constitutes an intake valve chest and it has also a bore 26 therein adjacent to the chamber 24 and extending upward from the lower end of the casting to constitute an intake valve cham-

ber. The stem 22 of the casting constitutes an exhaust valve chest and it has a bore 27 extending upward from the bottom of the casting to constitute an exhaust valve chamber. The wall of the valve chest between the air-chamber 24 and the valve chamber 26 has an intake port 28 therein and the wall of the valve chamber has also a port 29 therein opposite to the port 28. The wall of the valve chamber 27 has a port 30 therein to admit exhaust air to the chamber. A conduit 31 is connected with the port 29 and also with the port 30. A branch conduit 32 is connected with the air-conducting pipe 19 and also with the conduit 31. The wall of the chamber 27 has also an exhaust port 33 therein opposite to or on the plane of the port 30. Another intake port 34 extends from the air-chamber 24 to the valve chamber 26 and the wall of the valve chamber has a port 35 opposite to the port 34. The wall of the valve chamber 27 has an intake port 36 therein above the port 30 and a conduit 37 is connected with the ports 35 and 36 to conduct exhaust air to the valve chamber 27, the wall of the latter having an exhaust port 38 on the plane of the port 36. A branch conduit 39 is connected with the pipe 20 and the conduit 37. Two cylindrical or piston valves 40 and 41 are provided which are substantially alike and are closely fitted to slide longitudinally in the valve chambers 26 and 27 respectively, the valves extending out beyond the chambers and having stop shoulders 42 and 42' to engage the walls of the cylinders and limit the inward travel of the valves. The valve 40 has a circumferential groove 43 to constitute a duct between the ports 28 and 29 and it has also a similar groove 44 to constitute, when the valve is moved outward in its chamber, a duct between the ports 34 and 35. The valve 41 also has a duct 45 to afford communication between the ducts 30 and 33 when the valve is moved inward, the valve having also a similar duct 46 to form communication between the ports 36 and 38 when the valve is moved outward. The base portion 23 of the casting has a bracket 47 thereon which supports a pivot 48 to which a tumbler beam 49 is connected between its ends, the beam being suitably connected at its two ends with stems 50 and 50' with which the valves are respectively provided, so that each connection is of a pivotal character permitting slight slipping contact of the beam with respect to the stem. Preferably a coil spring is connected to and strained between the two stems to resist the tendency of the beam to force the two stems apart or outwardly each from the other. The arrangement is such, as will be seen, that the beam synchronously connects the two valves together in such relation that when either valve is set in its inward posi-

tion, the other valve is held in its outward position, so that the ducts of the valves shall have proper relation to the various ports of the valve chambers. Suitable provision is 5 made for holding the tumbler beam in its required positions and preferably comprises a bracket 52 which is fixed on the wall of the chamber 27, a hollow cylinder 53 having trunnions 54 supported in the bracket so as 10 to be on a plane horizontal with the pivot 48, a push bar 55 slidingly guided in the cylinder and having contact with the adjacent end of the beam 49, and a spring 56 arranged in the cylinder and yieldingly forcing 15 the push bar against the beam, so that when the adjacent end of the beam is pushed downward, the push bar exerts its force downwardly, and likewise when the end of the beam is moved upward the push bar acts 20 to hold it up, thus preventing accidental movement of the air-controlling valves.

For the purpose of enabling the compressed air when flowing in either of the air-conducting pipes 19 and 20 to be utilized for 25 actuating the air-controlling valves 40 and 41 automatically, suitable governing appliances are provided which preferably comprise two receptacles 57 and 58 that are connected by means of branch pipes 59 and 30 60 with the pipes 19 and 20, respectively and provided respectively with needle-feed valves 61 and 62. The receptacles are connected by means of conduits 63 and 64 with the upper portions of the chambers 26 and 27 respectively 35 to permit air to pass into the valve chambers, the walls of the latter having outlet ports 65 and 66 respectively to permit the escape of air when the valves uncover the ports, the ports being covered and closed 40 when the valves are moved inward to their full extent. The needle-feed valves are to be set so as to slowly admit the air into the receptacles during the time the compressed air acts to force the water out of the cylinder 45 chambers.

Preferably the exhaust ports 33 and 38 are provided respectively with exhaust pipes 67 and 68 to which a single exhaust pipe 69 is preferably connected. 50 The supply pipe 25 preferably has a valve 70 which may be used to stop the flow of air, or to restrict the passage of the air as a throttle in case the air pressure is greater than necessary for the operation of the 55 pump. The supply pipe has also a valve body 71 connected thereto and is supplied with compressed air either directly by an air compressor or through a reservoir 72. The valve body 71 has a port 73 extending there- 60 through and also a suitable movable valve therein adapted to either stop the flow or permit full flow of compressed air through the supply pipe. Preferably the valve is formed as a cylindrical rod or piston valve 65 74 that is longitudinally movable and ex-

tends through the valve body, the valve having a transverse port 75 to form communication with the port 73, the latter port being closed by the valve when the latter is moved to carry the port 75 away. An armature 76 is connected to one end of the valve, a similar armature 77 being connected to the opposite end of the valve, and preferably two yokes 78 and 79 are connected to the armatures. A base plate 80 is provided 75 and arranged in proximity to the valve body and supports an electro-magnet 81 opposite to the armature 76 and also an electro-magnet 82 opposite to the armature 77, the arrangement being such that the electro-magnets 80 are opposed each to the other, and when one electro-magnet draws the adjacent armature thereto, the opposite armature is drawn slightly away from the opposite electro-magnet, whereby the valve is opened or 85 closed. An electrical circuit wire 83 is connected with the electro-magnet 81, a circuit wire 84 being connected with the electro-magnet 82, both circuit wires being joined to a circuit wire 85 which is connected with 90 a suitable source of electricity, as a battery 86.

For the purpose of advantageously controlling the action of the electro-magnetically operated air-supply valve, the body 95 16 of the faucet or outlet valve is provided with an insulator 87 and the handle 18 of the rotary valve is provided with a switch point 88 arranged to sweep the surface of the insulator during movement of the handle. 100 A contact point or plate 89 is embedded in the insulator and has a circuit wire 90 connected therewith that is connected with the electro-magnet 81, the arrangement permitting the electrical circuit to be established when 105 the valve is opened to nearly full position, the circuit being broken when the valve is further moved to full open position. Another contact point or plate 91 is embedded also in the insulator 87 and has a circuit 110 wire 92 connected therewith that is connected with the electro-magnet 82 to establish the electrical circuit and energize the electro-magnet when the handle 18 is moved so as to nearly close the valve, the 115 circuit being broken when the valve is further moved to closed position. It will be seen that the electro-magnets operate alternately and that after each operation the valve 74 remains in the position to which it 120 may have been moved. Preferably a spring latch 93 is mounted on the base 80 to engage one of the armatures to prevent accidental movement of the valve.

Preferably the operative mechanism of 125 the pump is provided with a casing 94 having a top 95 which is secured to the wall of the air-chamber 24 and also to the wall of the valve chamber 27, the casing preferably being arranged on a main base or support 130

96 to which the base 80 may be secured, and to afford stability the stem 22 is provided with a boss 97 which extends through and is secured to the top 95. The casing preferably is so designed as to include front doors 98 and 99.

The pump is suitable for use in various situations and under different conditions, either in shops or factories, dwellings or 10 elsewhere and is particularly advantageous where fresh water is desired, and also when liquids are to be elevated and particularly when inexpensive low pressure air compressors are available, the air usually being compressed and delivered through a pipe 100 to the reservoir 72 from which the compressed air may be used when the air compressor is not in operation.

In practical use, a supply of compressed 20 air being assumed, in order to start the pump the handle 18 is turned to bring the contact point 88 to the contact point or plate 89, which establishes electrical connections resulting in energizing the electro-magnet 81 which draws to it the armature 76, whereby the valve 74 is moved to open position and permits the compressed air to pass to the air chamber 24, the valve 70 being open or adjusted as may be desired. 25 Assuming that the port 28 is open, the air passes by the valve 40 to the conduit 31 and thence through the branch 32 to the air-conducting pipe 19 and thence into one chamber of the pump cylinder 2, the valve 41 at 30 the same time being in its outward position and closing the port 30. Assuming that the pump cylinder is full or nearly full of the liquid or water from the well which may enter through the apertures 7 and 7', the 35 air pressure on the top of the water in the chamber forces the water through the valve casing 14 and up through the outlet pipe 11 to and through the discharge pipe 13 and thence out of the outlet faucet or 40 valve, the valve in the casing 14' preventing the water from passing down and out through the pipe 12. During the time that the air is passing through the pipe 19 a 45 relatively small portion of the air passes by the adjusted valve 61 and into the receptacle 57 and thence into the valve chamber 26. The receptacle becomes slowly filled with air which at first expands into the receptacle until compression is produced in 50 the receptacle sufficient to force the valve 40 outward to close the port 28 and open the port 34, such result occurring when the chamber in the pump cylinder has become entirely or nearly emptied, the valve 61 55 having been adjusted to obtain the timing effect required. The movement of the valve 40 actuates the beam 49 which obviously moves the valve 41 inward, so that while the air first utilized escapes from the pipe 60 19 into the conduit 31 and thence through 65

the port 30 and also through the duct 45 and out of the exhaust port 33, the valve 40 being then in position to close the port 29. The air pressure being released the chamber in the pump cylinder again becomes charged 70 as before. The water is then forced from the opposite chamber of the pump cylinder in like manner by means of the compressed air which passes through the port 34, the duct 44, the port 35 and thence through 75 the conduit 37 and through the branch 39 to the air-conducting pipe 20, the valve 41 preventing passage of the air through the port 36. A portion of the air passes by the valve 62 and into the receptacle 58 and 80 thence into the valve chamber 27, finally causing the valve 41 to move outward, thus reversing the valves and returning them to the position indicated in Fig. 6 and permitting 85 the air last utilized to pass out through the port 36, through the duct 46 and out through the exhaust port 38, after which the operation is repeated during the continuance of the supply of compressed air, with the result that the water is forced out 90 with a practically continuous flow. When it is desired to stop the pump the handle 18 is turned so as to close the outlet valve, and in doing so the contact point 88 engages the point or plate 91 to complete the electrical 95 circuit and immediately breaks the circuit as the valve is entirely closed, the established circuit causing energizing of the electro-magnet 82 which attracts and moves the armature 77 which draws the valve 74 100 to closed position, thus stopping the supply of compressed air and consequently the operation of the pump.

Having thus described the invention, what is claimed as new is—

1. A pneumatic pump including a pump cylinder, a discharge pipe connected with the cylinder, a pipe for conducting compressed air connected with the cylinder and provided with automatically-operable controlling means for controlling flow of the air to or from the air-conducting pipe, an independently-operable starting-valve for admitting compressed air to the controlling means provided with controllable operating means, and an outlet valve connected with the discharge pipe and having controlling means controlled by the operation of the valve for controlling the operation of the controllable operating means.

2. A pneumatic pump comprising two pump chambers each with an inlet valve and an outlet valve, two air-conducting pipes connected with the pump chambers respectively, two valve chambers of which one is an intake and the other an exhaust chamber, one end of each being open, each valve chamber having two inlet ports and two outlet ports, two controlling valves movable in the valve chambers respectively and extending 125

- beyond the open ends thereof, each controlling valve having ducts to alternately open and close the inlet ports and the outlet ports of the chamber, a tumbler beam pivotally supported and connected with the controlling valves, a conduit connected with one of the outlet ports of the intake valve chamber and also with one of the intake ports of the exhaust valve chamber and having a branch connected with one of the air-conducting pipes, a conduit connected with the remaining one of the outlet ports of the intake valve chamber and also with the remaining one of the inlet ports of the exhaust valve chamber and having a branch connected with the remaining one of the air-conducting pipes, an air-controlling conduit connected with the air-conducting pipe with which the first-mentioned branch is connected and also connected with the intake valve chamber beyond the inner end of the valve therein, and an air-controlling conduit connected with the remaining one of the air-conducting pipes and also with the exhaust valve chamber beyond the inner end of the valve therein.
3. In a pneumatic pump, the combination of a hollow cylinder, a partition longitudinally arranged in and dividing the cylinder into two chambers, two bottom heads secured to one end of the cylinder and the partition to close the chambers respectively, each head having an external hollow guide and also an aperture on either side of the guide, two foot valves to normally seat upon the heads respectively and close the apertures therein, each valve having a stem movably guided in the hollow guide of the head, two top heads secured to the opposite end of the cylinder and the partition to close the chambers respectively, two outlet pipes extending through and secured to the top heads respectively, the outlet pipes extending nearly to the foot valves respectively, two valve cases secured to the outlet pipes adjacent to the foot valves respectively, each case having a check valve therein, and two air-conducting pipes secured to the top heads and having connection with the chambers respectively.
- 50 4. In a pneumatic pump, the combination with a plurality of pump chambers with inlet and outlet valves, discharge pipes extending from the outlet valves, and a plurality of air-conducting pipes connected with the pump chambers respectively, of an intake valve chamber having inlet ports and outlet ports, an exhaust valve chamber having inlet ports and outlet ports, two valves operatively connected each with the other and movable in the valve chambers respectively to open or close the ports synchronously, a conduit connected with one of the outlet ports of the intake valve chamber and also with one of the inlet ports of the exhaust valve chamber and having a branch con-
- nected with one of the air-conducting pipes, and a conduit connected with another of the outlet ports of the intake valve chamber and also with another of the inlet ports of the exhaust valve chamber and having a branch connected with the remaining one of the air-conducting pipes.
5. In a pneumatic pump, the combination with a cylinder having two pump chambers, and two air-conducting pipes connected with the two chambers respectively, of a body structure comprising a base portion and two stems fixed on the base portion, each one of the stems having a valve chamber therein, one of the stems having also an air-chamber adjacent to the valve chamber with ports between them, a conduit connected with the two valve chambers and one of the air-conducting pipes, a conduit connected with the two valve chambers and the remaining one of the air-conducting pipes, two valves in the valve chambers respectively to control the flow of air from the chamber that is in communication with the air-chamber to the air-conducting pipes and from the latter to the remaining one of the valve chambers.
6. In a pneumatic pump, the combination with a pump chamber, of means for controlling the passage of air to or from the pump chamber, said means comprising a valve chamber having two inlet ports and two outlet ports, one end of the valve chamber being open, the valve chamber having an exhaust port at a distance from the opposite end thereof, a valve longitudinally movable in the valve chamber and closing said open end, the valve being stopped from movement after closing said exhaust port and having a duct to open one of the inlet ports and one of the outlet ports and having also another duct to periodically open the remaining inlet and outlet ports, and means for automatically conducting air to the valve chamber beyond the valve when the exhaust port is closed to reverse the valve.
7. In a pneumatic pump, the combination with pump chambers, of air-conducting pipes connected with the chambers respectively, a base having a pivot thereon, two valve chambers fixed on the base and having ports to direct air to and from the air-conducting pipes, two valves movable in the valve chambers respectively to control the opening and closing of the ports, a beam mounted to rock on said pivot and connected with the valves, a bracket fixed on said base, a hollow cylinder mounted to rock on said bracket, a push-bar movable in said cylinder and engaging one end of said beam, and a spring in said cylinder acting on and yieldingly projecting said push-bar.
8. In a pneumatic pump, means for controlling the passage of air comprising an intake valve chest and an exhaust valve chest

rigidly connected together, each chest having two inlet ports and two outlet ports, two controlling valves movable in the chests respectively and operatively connected each 5 with the other for synchronous movement, each controlling valve having ducts to alternately open and close the inlet ports and the outlet ports of its chest, two air-conducting pipes, a conduit connected with one of 10 the outlet ports of the intake valve chest and also with one of the inlet ports of the exhaust valve chest and having a branch connected with one of the air-conducting pipes, a conduit connected with the remaining 15 one of the outlet ports of the intake valve chest and also with the remaining one of the inlet ports of the exhaust valve chest and having a branch connected with the remaining one of the air-conducting pipes, 20 and an air-supply conduit having two ports extending into the intake valve chest and controlled by the controlling valve therein.

9. In a pneumatic pump, means for controlling the passage of air comprising an 25 intake valve chest and an exhaust valve chest connected together, each chest having inlet ports and outlet ports, two controlling valves connected together and movable in the valve chests respectively to open or close 30 the ports, two air-conducting pipes, a conduit connected with one of the outlet ports

of the intake valve chest and also with one of the inlet ports of the exhaust valve chest and having a branch connected with one of the air-conducting pipes, a conduit connected with another one of the outlet ports of the intake valve chest and also with another one of the inlet ports of the exhaust valve chest and having a branch connected with the remaining one of the air-conducting 40 pipes, an air-controlling conduit connected with the air-conducting pipe with which the first-mentioned branch is connected and provided with a regulating valve, an air-controlling conduit connected with the remaining one of the air-conducting pipes, a fluid-holding receptacle connected with the regulating valve of the first-mentioned air-controlling conduit and having connection with the intake valve chest beyond one end of the valve therein, and a fluid-holding receptacle connected with the regulating valve of the remaining air-controlling conduit and having connection with the exhaust valve chest beyond one end of the valve 50 therein.

In testimony whereof, I affix my signature in presence of two witnesses.
